UNITED STATES PATENT OFFICE.

BYRAM C. TRUEBLOOD, OF FREEPORT, ILLINOIS, ASSIGNOR TO ARCADE MANUFACTURING COMPANY, OF FREEPORT, ILLINOIS, A CORPORATION OF ILLINOIS.

DESIGN FOR A CASING FOR A COFFEE MILL.

Application filed October 31, 1921. Serial No. 511,935. Term of patent 14 years.

To all whom it may concern:

Be it known that I, BYRAM C. TRUEBLOOD, a citizen of the United States, residing in the city of Freeport, county of Stephenson, and State of Illinois, have invented a new, original, and ornamental Design for a Casing for a Coffee Mill, of which the following is a specification, reference being had to the accompanying drawing, forming part hereof.

The figure is a perspective view of a casing for a coffee mill, showing my new design.

I claim:

The ornamental design for a casing for a coffee mill, as shown.

BYRAM C. TRUEBLOOD,
